J. W. Corey,

Washing Machine,

No. 12,757.

Patented APR. 24, 1855.

UNITED STATES PATENT OFFICE.

JASON W. COREY, OF CRAWFORDSVILLE, INDIANA.

SPRING CONNECTING-ROD FOR WASHING-MACHINES.

Specification of Letters Patent No. 12,757, dated April 24, 1855.

To all whom it may concern:

Be it known that I, JASON W. COREY, of 5
Crawfordsville, in the county of Montgomery
and State of Indiana, have invented a
new and useful Machine for Washing and
Cleaning Clothes, &c.; and I hereby declare
the following is a full, clear, and exact description
of the construction and operation
of the same, reference being had to the an- 10
nexed drawings, making a part of this speci-
fication, in which—

Figure 1, is a perspective view of the machine: Fig. 3 is a section of the eccentric showing the groove and eccentric strap: 15 Fig. 2 is a view of the eccentric, with the coiled spring: Fig. 4 is a view of the eccentric strap, showing the regulating binder, and a section of the coiled spring: Fig. 5 is an enlarged view of the regulating binder: 20 Fig. 6 is a perspective view of the dasher, showing its operation on the guides, and also the operation of the rocking cross-head: Fig. 7 represents the slats in the corner and bottom of the box, against which the clothes 25 are beaten by the dasher.

The following is a description of the construction of the machine, reference being had to the drawings.

Similar letters refer to like parts. 30 The nature of the machine consists in a new mode of washing and cleansing clothes, &c., the principal feature of which is a dasher or beater moved backward and forward on guides, in a water-tight box, by means of a coiled spring connected to an eccentric. 35

A A represents the interior of the box, in which the water is poured, and the clothes placed.

40 B is the dasher, with leaves (g g g), slides (d d) and a rocking cross head (J), attached to the coiled spring (C).

C shows the coiled spring, encircling the eccentric, thus constructed, with coils, for the purpose of preventing, by reason of its pliancy in that form, too great pressure and strain upon the clothes.

45 D D shows the guide or iron rod, passing through the interior of the box on the left side, firmly secured at the ends of the box by taps, and upon which the dasher (B) is hung by slides (d d) at both ends, so as to touch neither the sides nor bottom of the box.

E is the eccentric.

55 F is the shaft to which the eccentric (E), the balance wheel (G), and the spur wheel (H) are attached.

I is a spur wheel, connected with the right side of the box, and turned by a crank (M). 60

J represents the cross head, made to turn in its sockets as it is worked by the coiled spring.

K is the regulating binder, through which the coiled spring passes, above the eccentric 65 strap (a), as will be more clearly seen in Fig. 5 c c being the slot for the spring, and b the slot for the strap.

The construction of the eccentric, eccentric strap, coiled spring, and binder are 70 plainly exhibited in Fig. 2; the spring and strap are connected at a in that figure. The eccentric E is grooved (as in Fig. 3) to retain the strap in its place, and at the same time allow the spring and strap to remain 75 stationary while the eccentric revolves.

The construction of the dasher (B) is shown in Fig. 6. The slides d d hang upon the guides D D. e e are the side pieces of the dasher to which leaves (g g g) are firmly 80 attached. The spring (C), after passing through the cross head, is made to allow the regulation of the reach of the dasher when in operation; by moving the cross head toward the spring, the reach is shortened, and 85 the reverse is effected by moving it from the spring.

L L as seen in Fig. 1, are slats grooved to present a surface as in Fig. 7, and secured in the bottom corners in the ends of the 90 water box.

The operation of the machine is as follows: The crank M communicates motion to the spur wheels I and H; H being on the shaft F revolves the eccentric E and balance 95 wheel G; the coiled spring C, encircling the eccentric, sets the dasher (B) in motion backward and forward on the guides (D D). The dasher agitates the water, and beats the clothes against the slats (L L), by which 100 means the clothes are kept in constant reyolution. The binder (K), being movable to any point around the eccentric, regulates the coiled spring, increasing or diminishing its stiffness.

105

I claim—

The coiled spring C, combined with the eccentric E, or its equivalent, for the pur-

poses specified, it being understood that I do not claim in general the device of a spring interposed between the eccentric, or its equivalent, and the beater, for the purpose of relieving an excess of pressure upon the clothes, as that device is not new in washing machines, but only the manner of

arranging and applying the spring, as specified in the above claim.

JASON W. COREY
